UNITED STATES PATENT OFFICE

2,557,767

MATERNITY GIRDLE

Mary E. Schlageter, Chicago, Ill., assignor to
Kabo, Inc., a corporation of Illinois

Application January 3, 1949, Serial No. 68,899

2 Claims. (Cl. 2—27)

1

This invention relates to a girdle, and particularly to adjustable means secured to said girdle to provide adequate body support for a pregnant woman.

During a woman's pregnancy it is very important to provide a girdle that will give her body a form as shapely as possible, and yet provide adequate support for helping the expectant mother carry her child without too much discomfort. A fixed support secured to the girdle is not suitable because, even though it is elastic, it can not always accommodate itself to the progressive changes of shape of the woman during her pregnancy and often binds and thus makes the wearer uncomfortable.

It is within the contemplation of the present invention to provide a girdle with supporting means that may be adjusted in position to accommodate different shapes assumed by a woman's body during pregnancy. The supporting means is designed to furnish proper support for the user's abdomen without pinching or binding any part of the expectant mother's body. For this purpose the girdle is provided with fastening means that may be laced tightly at any points desired, and loosely at other points where comfort is more important than appearance. A pair of bands are crossed in the front portion of the girdle to furnish extra support for the user's abdomen and are adjustable vertically relative to the girdle to move the support to where it is needed.

The structure by which the above advantages are attained will be described in the following specification, taken in conjunction with the accompanying drawing, in which:

Figure 1 is a front view of the maternity girdle embodying the invention as worn by a woman;

Fig. 2 is a rear view of the girdle with a portion of the back broken away to show the vertically adjustable crossed supporting bands;

Fig. 3 is a cross sectional view through the girdle, taken along the line 3—3 of Fig. 1; and

Fig. 4 is an enlarged view of the girdle turned inside out to show the fastening means which permit vertical adjustment of the crossed supporting bands.

In the drawings, the reference numeral 2 indicates the front portion of a girdle which is joined to a back portion 3 by means of a pair of gussets or inserts 4 and 5. The front and back portions are preferably made of two-way stretch elastic fabric and the inserts of thin non-elastic fabric. A row of loops 6 extends along each opposite edge of both front and back portions, and laces 7 are

threaded through the loops. The laces are long enough so that they may be tied as tightly or as loosely as desired, at any intermediate point, as indicated at 8 and 9, for example, as well as at the ends, so that the fastening of the girdle by these laces may provide some degree of support and comfort for the wearer. It is obvious that the gussets will provide for expansion of the girdle as the wearer increases in size.

10 A pair of bands 10 and 11, crossed inside front portion 2, preferably in X formation, provide extra support for the wearer's abdomen. The bands are preferably stitched together to form a single unit and are of substantial height to prevent undesired binding pressures on very limited portions of the wearer's body. Each pair of corresponding ends of the bands are stitched to a strip 12 of any suitable strong fabric to which a series of hooks 13 is secured. A strip 14, similar to strip 12, secured to front panel 2 at each side thereof, carries a series of eyes 15 at intervals spaced to correspond to the spacing of hooks 13. A soft flannel flap 16 is secured to each strip 14 so as to overlie the eyes and also the hooks when 25 the hooks are engaged with the eyes. The flannel strips furnish protection to the wearer's skin and keep the fastening means from pinching or bruising the skin.

30 The number of hooks on each strip 12 is less than the number of eyes on the corresponding strip 14 so that the bands may be adjusted vertically relative to the girdle. This arrangement is of particular importance to pregnant women because it permits the bands to give the extra support where it is needed without binding at sensitive portions of the body. Some women carry babies higher than others and the supporting bands of the girdle of the present invention may be adjusted to provide comfort and support to the wearer during all stages of her pregnancy. The support thus may follow the body contour changes.

40 The supporting bands are detachably secured at each end and, if the extra support is not required, the bands may be removed and the girdle worn as a regular girdle. The laces may be pulled tightly along the entire length of the garment to make it follow closely the body contour. Conventional garter supporters 17 are secured to 45 the lower edge of the girdle.

45 It will be obvious that any suitable fastening means may be substituted for hooks 13 and eyes 15. For example, snap fasteners may be used. The only essential requirement is that the fastening element that is secured to the girdle exceed

in number the cooperating fastener elements secured to the edges of the supporting bands, so that the supporting bands may be secured in a plurality of different positions relative to the height of the girdle.

Although I have described a preferred embodiment of the invention in considerable detail, it will be understood that the description is intended to be illustrative, rather than restrictive, as many details may be modified or changed without departing from the spirit or scope of the invention. Accordingly, I do not desire to be restricted to the exact structure described.

I claim:

1. A maternity girdle comprising a front portion, a back portion, a gusset on each side joining said front and back portions, abdominal supporting means detachably secured to the inner surface of said front portion, said abdominal supporting means consisting of a pair of transverse bands stitched together to form a single X-shaped unit, a pair of strips, the adjacent ends of the said bands on opposite sides of the X-shaped unit being secured to one of said strips, thereby preventing relative movement between said ends, a plurality of vertically aligned fastening means on each of said strips, and a plurality of vertically aligned cooperating fastening means on opposite sides of the inner surface of said front portion, each of said last named fastening means being greater in number than the first named fastening means whereby said abdominal supporting means may be vertically adjusted relative to said front portion.

2. A girdle comprising a front portion, a back portion, a panel on each side joining said front and back portions, abdominal supporting means detachably secured to the inner surface of said front portion, said abdominal supporting means consisting of a pair of transverse bands arranged to form a single X-shaped unit, a pair of strips, the adjacent ends of the said bands on opposite sides of the X-shaped unit being secured to one of said strips, thereby preventing relative movement between said ends, a plurality of vertically aligned fastening means on each of said strips, and a plurality of vertically aligned cooperating fastening means on opposite sides of the inner surface of said front portion, each of said last named fastening means being greater in number than the first named fastening means whereby said abdominal supporting means may be vertically adjusted relative to said front portion.
